HARD SURFACE FLOOR COVERING OR SIMILAR ARTICLE

George W. Johnson, San Francisco, Calif., as
signor to Pabco Products Inc., San Francisco,
Calif., a corporation of Delaware

Application November 9, 1953, Serial No. 27,496

Term of patent 3½ years

(Cl. D92—17)

To all whom it may concern:

Be it known that I, George W. Johnson, a citizen of the United States, residing in the city and county of San Francisco, State of California, have invented a new, original, and ornamental Design for a Hard Surface Floor Covering or Similar Article, of which the following is a specification, reference being had to the accompanying drawing, forming part thereof.

The drawing is a plan view of a piece of hard surface floor covering or similar article showing my design. On such drawing, the broken lines outline a design unit which is repeated in regular succession as indicated by the extensions beyond the boundaries of such unit.

I claim:

The ornamental design for a hard surface floor covering or similar article, substantially as shown and described.
